UNITED STATES PATENT OFFICE.

DEUNBORD BEAUDRY, OF MONTREAL, QUEBEC, CANADA.

WASH-BENCH.

SPECIFICATION forming part of Letters Patent No. 357,304, dated February 8, 1887.

Application filed August 12, 1886. Serial No. 210,750. (No model.)

To all whom it may concern:

Be it known that I, DEUNBORD BEAUDRY, a citizen of Canada, residing in the city and district of Montreal, in the Province of Quebec, Canada, have invented a new and useful Improvement in Combination Wash-Benches, of which the following is a specification.

The object of my invention is to provide a wash-bench of such construction that it may be arranged in a variety of shapes to serve different purposes; and to this end my combination wash-bench is constructed substantially in the manner hereinafter described, reference being had to the accompanying drawings, in which—

Figure 1 is a front view of the bench as arranged for washing, and Fig. 2 is a transverse section of the same on line *x x*. Fig. 3 is a front view of the bench as arranged for an ironing-table, and Fig. 4 is an end view of the same. Fig. 5 is a front view of the bench as formed into a seat with back and arms, and Fig. 6 is an end view of the same. Fig. 7 is a front view of the bench as folded up for shipment or stowing away, and Fig. 8 is an end view of the same.

Similar letters indicate the same parts in the several views.

The part indicated by the letter *A* is the top of the wash-bench. It is supported by and secured to the braced standards *B*, in which are formed the hinges *a*, which allow these standards to be folded snugly under the top *A* when not in use. To the rear edge of the top *A* is hinged the extension-board *C*, which when laid out horizontally, as shown in Fig. 2, forms a sufficiently-wide bench to hold the wash-tubs, which are indicated by dotted lines. When the extension-board *C* is thus laid out for use, its outer edge is supported by the back-board *D*, which is hinged to its outer edge by the hinges *b*. In the braces *c* of the standards *B* a vertical slot is made for the purpose of receiving the bar *E*, by which the standards *B* are kept from folding under and the bench kept rigidly upright. When the bench is to be used as an ironing-table, the extension-board *C* is turned upright, as shown in Fig.

4. *d d* are two arms pivoted to the ends of the extension-board, and provided with hooks

on their ends, which take over the screws *e* in the tops of standards *f*, and the extension-board is thus braced in an upright position. These arms *d* are also provided with a series of socket-holes, *j*, to enable the board *C* to be adjusted at an angle, thus lowering or raising the back-board *D*. The back-board *D* folds over horizontally and becomes the ironing-table, two of the drying-rods *g* being placed as supports under its front edge.

F represents a skirt-ironing board, such as now commonly used for that purpose. It is provided with the rib *h*, which supports it at a suitable distance above the table, and allows such articles as skirts and pantaloons-legs, &c., to be passed around it, in order to be properly ironed. This skirt-board may be held in a position parallel to the table by the clamp *i*, Fig. 3, which holds the end of the skirt-board which is nearest the rib *h* against rising too high. Some of the drying-rods *g*, of which there may be any desired number, may be placed in the socket-holes *j* in the arms *d*, from which they project outward and serve to support the laundered articles. When not required for use, these rods may be stowed away in the rack *k*, which is attached to the back-board *D*. The wash-bench top *A* will also be found a convenient depository for articles that have been ironed.

My combined wash-bench is quickly and easily changed from an ironing-table into a seat by simply turning the back-board *D* over backward and allowing it to hang down vertically behind the seat.

The bench is packed, as shown in Figs. 7 and 8, for stowing away or shipment by first folding the extension and back boards down upon the top *A*. The skirt-board *F* is then placed in the holder *l*, which is attached to the back-board and held by clamp *i*. The bar *E* is then lifted out of the slots in the braces *c* and placed over the braces of the standards *B* as they lie folded down, and over the holder *l*, where it is held by the headed stud *m*, which is fixed in the holder, and projects up through the slot *n* in the bar.

What I claim as my invention in the above-described combination wash-bench is—

1. The combination of the top *A*, standards

- B, having the hinges *a* and trusses *c*, the bar *E*, provided with a slot, and the pin *m* on the holder *l* for engaging with said slot, substantially as and for the purpose set forth.
- 5 2. The combination of the back-board hinged to the extension-board *C*, and the extension-board *C*, hinged to the bench-top *A*, with the folding standards *B* and the bar *E*, as shown, and for the purpose set forth.
- 10 3. The combination of the table-top, the braced folding standards *B*, standards *f*, formed on said standards *B*, the extension-board *C*, and the arms *d*, pivoted to said standards and board and having a series of socket-holes, *j*, and also 15 hooks on their ends to engage with the stand-
- ards *f*, substantially as and for the purpose described.
4. The combination of the folding standards *B*, the extension-board *C*, the standards *f*, the arms *d*, pivoted to the extension-board *C* and 20 hooked to the standards *f*, and provided with socket-holes *j*, the back-board *D*, rack *k*, drying-rods *g*, and bench-top *A*, substantially as described.

Signed at Montreal this 14th day of July, 25
A. D. 1886.

DEUNBORD BEAUDRY.

In presence of—

JOSEPH PAQUETTE,
F. RIEUTORD.
